UNITED STATES PATENT OFFICE.

HALBERT K. HITCHCOCK, OF PITTSBURGH, PENNSYLVANIA, ASSIGNOR TO THE ENTERPRISE MANUFACTURING COMPANY, OF AKRON, OHIO, A CORPORATION OF OHIO.

COLLAPSIBLE CAMPERS' STOVE.

1,238,142.

Specification of Letters Patent. Patented Aug. 28, 1917.

Application filed August 17, 1916. Serial No. 115,475.

To all whom it may concern:

Be it known that I, HALBERT K. HITCHCOCK, a citizen of the United States, residing at Pittsburgh, in the county of Allegheny and State of Pennsylvania, have invented new and useful Improvements in 5 Collapsible Campers' Stoves, of which the following is a specification.

This invention relates to improvements in 10 portable cooking stoves such as are commonly used by tourists, campers, hunters, etc. The object of the invention is to provide a simple and efficient device of the character named which can be easily transported 15 and collapsed to occupy a minimum amount of space and in which fire can be easily built and maintained and provided with a table or top for sustaining a cooking utensil. A further object of the invention is to make 20 the device as light as possible and so constructed that it can be folded into a comparatively flat form to thereby render the same compact to permit its being easily carried without inconvenience.

With the foregoing and other objects in view, the invention consists in the novel construction, combination and arrangement of parts constituting the invention to be hereinafter specifically described and illustrated 25 in the accompanying drawings which form a part hereof wherein is shown the preferred embodiment of the invention, but it is to be understood that changes, variations and modifications can be resorted to which come 30 within the scope of the matter hereinafter claimed.

In the drawings in which similar reference numerals indicate like parts in the different figures,

40 Figure 1, is a perspective view of the device in its open position.

Fig. 2, is a similar view showing the same with the walls partially moved toward their collapsed position.

45 Fig. 3, is a view similar to Fig. 2 with the walls moved farther toward a collapsed position, and

Fig. 4, is a perspective view of the device in its collapsed condition.

50 The device embodies four side members, 1, 2, 3 and 4 all preferably constructed of thin sheet metal and each preferably fashioned in the general form of a trapezoid. The members 1 and 2 are preferably al-

though not necessarily slightly narrower 55 transversely than the members 3 and 4 for a purpose to be later described. The member 1 is provided with integral tubular lugs 5 along one side arranged in spaced relation and with the openings thereof in alinement. 60 The opposite side is provided with similar tubular lugs 6 also arranged in spaced relation. The member 2 is provided along one side with tubular lugs 7 arranged in spaced relation and of proper length to be positioned between the lugs 5 of the member 1 to thereby form a hinge joint, the pivot for which is a pin or wire 8. The opposite side of the member 2 is provided with integral tubular spaced lugs 9 with the openings 70 thereof in alinement. The member 3 is provided along one side with tubular lugs 10 arranged in spaced relation and adapted to be inserted in the spaces between the lugs 6 of the member 1 and extending through the 75 openings in the lugs 6 and 10 is a removable wire or pin 11 to form a hinge joint. The member 4 is provided along one side with tubular lugs 12 alternating in position with respect to the lugs 9 of the member 2 and 80 are arranged to be inserted between them and form a hinged connection between the two by means to be later described. The member 4 on its opposite side is provided with tubular lugs 13 and the member 3 is 85 provided on one side with tubular lugs 14, the lugs 13 and 14 alternating in position with respect to each other. Extending through the lugs 9 and 12 of the members 2 and 4 and also through the lugs 13 and 14 90 of the members 3 and 4 is a U-shaped wire 95 constituting a pivotal connection for the members 2 and 4 on one side and the members 3 and 4 on the other side and this wire extends from the upper end of the lug 9 of the member 2 to the upper portion of the lug 13 of the member 4 to form a straight portion 16. The members 1 to 4 inclusive are provided in their upper edges with approximately semi-circular notches 17 thereby 100 providing openings 18 for a purpose to be later described. The members 1 to 4 inclusive are also provided with openings 19 for a purpose to be later described. When the various members 1 to 4 inclusive are in their open or expanded position they form 105 a hollow frustum of a pyramid and constitute the side walls of the stove.

- The top 20 of the stove consists of a sheet of metal provided at one side with tubular lugs 21 inclosing the portion 16 of the wire 15 to form a hinged connection therewith.
- 5 The member 20 is furthermore provided along its edges with inwardly-extending notches 22 for a purpose to be later described and the member 20 is of such length so that its free ends 23 rest upon the upper 10 portion of the member 1, between the upper ends of the pins 8 and 11 which serve to prevent lateral motion of the top or cover 20 and this engagement serves to hold the device in its open or expanded condition.
- 15 When the device is in its open or expanded condition as shown in Fig. 1, fire may be built within the device and draft for the proper combustion is furnished by the openings 18 and 19 and the products of combustion pass upwardly through the openings formed by the notches 22 for the heating of a utensil which may be seated on the top member 20.

When it is desired to collapse the device 25 where the members 1 and 2, as before stated are slightly narrower than the members 3 and 4 the latter are moved inwardly so as to bring the pin or wire 8 into close engagement with the portion of the wire 15 which 30 extends through the lugs 13 and 14 thereby bringing the member 1 into substantial contact or close proximity to the member 3 and the member 2 into similar relation with respect to the member 4. The pair of members 1 and 3 are then moved on their respective pivots to bring them into close proximity to the pair of members 2 and 4 and the cover 20 may be swung backwardly to lie against the outer face of the member 40 4 so that when in its collapsed condition the device will be as shown in Fig. 4.

The foregoing manner of collapsing the stove is peculiarly applicable in cases where the members 1 and 2 are narrower transversely than the members 3 and 4, as being the best and easiest manner of collapsing the 45

stove, but it will be obvious, of course, that the pivot pin 11 may be withdrawn so as to permit the separation of the lugs 6 from the lugs 10 and the members may be folded one 50 over another so as to form as compact a condition as that shown in Fig. 4.

It is entirely obvious, of course, that all of the members 1 to 4 inclusive may be of equal width and in this latter case the second manner of folding or collapsing the 55 stove is preferable. Furthermore it is equally true that instead of making all of the members 1 to 4 in the form of a trapezoid in side elevation they may be formed 60 rectilinearly and the stove perform all the functions equally well, however, the trapezoid form is the preferred one.

I claim—

A portable cooking stove comprising four 65 side members each in the form of a trapezoid in side elevation and each provided along the lateral edges thereof with hinge forming members, pivot pins for two of the joints between three of the members and a 70 U-shaped member constituting a pivot pin for the other two joints of the device, a portion of said U-shaped member extending between said last named joints and having the sides thereof constituting a support, with 75 the named portion constituting a hand grip in carrying, a cover mounted on said support adapted to rest on the top of one member, said members provided with draft openings, said cover provided with lateral 80 notches to form an up-take passage for the products of combustion, two of said members being narrower than two of the other members to permit the infolding of the narrower members against said wider members 85 and the subsequent book-wise folding of said wider members about said narrower members.

In testimony whereof I have hereunto set my hand.

HALBERT K. HITCHCOCK.
